UNITED STATES PATENT OFFICE

FRED C. FANTZ, OF WEBSTER GROVES, MISSOURI

RETURN BEND FITTINGS FOR OIL STILLS

Original application filed December 8, 1931, Serial No. 579,707. Divided and this application filed February 3, 1932. Serial No. 590,629.

My invention relates to that class of return bends such as are described in my co-pending application, Serial No. 579,707, of which this application is a division.

5 Return bends of this type are principally used to connect tubes in oil stills where they are subjected to both high pressures and temperatures so that they must be of very rugged construction in order to withstand the 10 conditions under which they are used. It is well known that generally the tubes are mounted in nests or banks with exceedingly close centers, therefore it is essential to provide a construction which will not only have 15 the requisite strength but this must be done in a very limited space.

My invention has for its object to construct a compound housing which will be capable of being swung laterally to disengage the 20 housing from the tubes.

My means of accomplishing the foregoing objects may be more readily understood by having reference to the accompanying drawing, which is hereunto annexed and made a 25 part hereof, in which—

Fig. 1 is a side elevation of a fragmentary part of a pair of still tubes connected by my improved type of return bend, a portion of the wall being broken away to show the 30 interior construction;

Fig. 2 is a vertical section on the lines 2—2 in Fig. 1; and

Fig. 3 is a similar view showing a different, though equivalent form of holding the 35 sections together.

Similar reference numerals refer to similar parts throughout the entire description.

As shown in the drawing, the tubes 1 and 2 are shown with their ends upset, forming shoulders 3. As seen in Fig. 2 the ends of these upset portions are beveled and adapted to contact corresponding surfaces on the faces of the return bend. As shown in Fig. 3 there is a ridge 5 projecting above the upset annular portion which is convex in cross section as clearly seen in Fig. 3. The return bend 6 shown in Fig. 3 connects the two tubes 1 and 2 each face 7 of the return bend being provided with an annular V shaped recess adapted to receive the ridge 5 and form a

tight joint. The return bend 6 is mounted in a compound housing. As illustrated it consists of two pairs of complementary sections 9 and 10, and 11 and 12, the lower portions 13 of which contact the tubes and partially 55 encircle the same. Shoulders 14 are formed on the inner surface of these lower portions 13 which are adapted to be locked to the shoulders 3 on the tubes. In view of the fact that the construction of each half of the 60 return bend is identical, I shall confine myself to a description of a single end. The complementary sections have upwardly extending arcuate side walls which serve as a 65 mounting for the tightening means. As illustrated these comprise portions 15 and 16, on the sections 9 and 10 and 11 and 12 respectively, the portion 15 on the section 9 has a boss 17 formed thereon which is provided with a central aperture which is 70 threaded. A set screw 18 is mounted in these threads, its inner end contacting one of the two abutments 19 formed on the external wall of the return bend 6. These 75 abutments 19 are formed with their centers on the center line of the tubes 1 and 2. The portion 16 of the section 10 has an aperture formed therein and is adapted to slip over the boss 17. The wall 20 of this aperture is slanted or flared outwardly so that the sections 80 may be swung outwardly as shown in dotted lines Fig. 2. My device illustrated in Figs. 1 and 2 has reinforcing rings 21 mounted on the tubes 1 and 2. The upper edge of each of the rings abuts the shoulder 3 85 upset on the tube, its lower edge is undercut to receive extensions 22 and 23 formed on the lower portions of the housing sections 9 and 10. The ring 21 engaging the extensions 22 and 23 serves to hold the housing sections 90 together. It will be apparent that by tightening the set screws 18 a tight joint will be produced between the return bend 6 and the tubes 1 and 2. In Fig. 3 I have shown extensions projecting downwardly and the 95 ring is mounted on them to hold the sections together. Where this equivalent form of construction is employed the upset portion of the tubes 1 and 2 which forms the shoulder 100 should be much heavier to furnish adequate

strength. Although I have shown specific details of construction, such as the mounting means for the tightening device and the housing made in four sections, I do not wish to be understood as limiting myself thereby for it will be obvious to persons who are skilled in the art that the housing may be made in two instead of four sections and that other tightening means may be substituted for the one described, it being my wish to illustrate only a preferred form to show a concrete embodiment of my invention and I wish to be limited only by such limitations as appear in the hereinafter contained claims.

Having described my invention what I regard as new and desire to secure by Letters Patent is:

1. In a refinery apparatus, a return bend, a pair of shouldered tubes communicating therewith, a compound housing therefor, comprising complementary sections adapted to partially encircle the ends of said tubes and to be locked to the shoulders on the tubes, a boss on one of said complementary sections there being an aperture in the other section in which said boss is mounted, the walls of said aperture being flared outwardly whereby the lower portions of said sections can be swung outwardly and a set screw in said boss adapted to contact said return bend to hold said tubes and return bend in a tight joint.

2. In a refinery apparatus, a return bend, a pair of shouldered tubes communicating therewith, a four part housing therefor, comprising complementary sections adapted to partially encircle the ends of said tubes and to be locked to the shoulders on the tubes, a boss on one of said complementary sections there being an aperture in the other section in which said boss is mounted, the walls of said aperture being flared outwardly whereby the lower portions of said sections can be swung outwardly, and a set screw in said boss adapted to contact said return bend to hold said tubes and return bend in a tight joint.

3. In a refinery apparatus, a return bend, a pair of shouldered tubes communicating therewith, a compound housing therefor, comprising complementary sections adapted to partially encircle the ends of said tubes and to be locked to the shoulders on the tubes, a boss on one of said complementary sections there being an aperture in the other section in which said boss is mounted, the walls of said aperture being flared outwardly whereby the lower portions of said sections can be swung outwardly, and a set screw in said boss adapted to contact said return bend to hold said tubes and return bend in a tight joint, a reinforcing ring on said tubes having its under surface undercut, extensions on said housing sections which engage said rings.

4. In a refinery apparatus, a return bend,

a pair of shouldered tubes communicating therewith, a compound housing therefor, comprising complementary sections adapted to partially encircle the ends of said tubes and to be locked to the shoulders on the tubes, a boss on one of said complementary sections there being an aperture in the other section in which said boss is mounted, the walls of said aperture being flared outwardly whereby the lower portions of said sections can be swung outwardly, and a set screw in said boss adapted to contact said return bend to hold said tubes and return bend in a tight joint, and means to hold said sections together.

5. In a refinery apparatus, a return bend adapted to connect a pair of shouldered tubes, of a compound housing therefor, comprising complementary sections having arcuate flanges adapted to be locked to the shoulders on the tubes, a boss on one of said complementary sections there being an aperture in the other section in which said boss is mounted, the walls of said aperture being flared outwardly whereby the lower portions of said sections can be swung outwardly, and a set screw in said boss adapted to contact said return bend to hold said tubes and return bend in a tight joint.

In witness whereof, I hereunto set my hand.

FRED C. FANTZ. 95
